UNITED STATES PATENT OFFICE.

GEORGE L. PIERCE, OF MANCHESTER, NEW HAMPSHIRE, ASSIGNOR TO PRESTO SPINNING RING HOLDER COMPANY, OF BOSTON, MASSACHUSETTS, A CORPORATION OF MAINE.

SPINNING-RING HOLDER.

1,109,869.

Specification of Letters Patent. Patented Sept. 8, 1914.

Application filed September 24, 1910. Serial No. 583,545.

To all whom it may concern:

Be it known that I, GEORGE L. PIERCE, a citizen of the United States, residing at Manchester, county of Hillsboro, State of New Hampshire, have invented an Improvement in Spinning-Ring Holders, of which the following description, in connection with the accompanying drawing, is a specification, like characters on the drawing representing like parts.

This invention relates to spinning ring holders of that type which are detachably secured to the ring rail or rail plate so that the spinning ring holder with its spinning ring can be readily removed from the rail plate without disturbing the latter to permit another spinning ring holder with its spinning ring to be substituted therefor.

The objects of the present invention are to provide a novel way of detachably fastening the spinning ring holder to the rail plate, all as more fully hereinafter described and then pointed out in the appended claims.

Referring to the drawings wherein I have shown one embodiment of my invention, Figure 1 is a plan view of a portion of a ring rail equipped with my improved spinning ring holder; Fig. 2 is a plan view of a rail plate adapted to receive my improved spinning ring holder; Fig. 3 is a plan view of the spinning ring holder detached; Fig. 4 is a side view of the spinning ring holder applied to the rail plate; Fig. 5 is a side view of a portion of the opposite side of the spinning ring holder and rail plate from that shown in Fig. 4; Fig. 6 is an enlarged section on the line *b*—*b*, Fig. 1.

In the drawings 3 designates a ring rail of any suitable construction which is provided with the usual apertures 4 through which the bobbin extends. Spinning rings of this type as now commonly made usually employ a rail plate which is secured to the ring rail 3 and is provided with an aperture 45 concentric with the aperture 4, and a ring holder which supports the spinning ring and which is secured to the rail plate. As stated above, one feature of my present invention relates to a novel manner of securing the ring holder to the rail plate.

In the drawings a rail plate is shown at 5 and it is provided with the aperture 6 concentric with the aperture 4 and is adapt-

ed to be secured to the ring rail 3 by any suitable means, such as screws 7. The ring holder is shown at 8 and it is provided with a central aperture as usual and is also provided with upturned ears or lips 9 which engage the lower flange of the usual spinning ring 10, this being a common method 60 of fastening the spinning ring to the ring holder. In the present improvement the rail plate is provided with a guiding projection which is adapted to be received in an opening formed in the ring holder and which is 65 constructed to permit the ring holder to be turned laterally about said projection as a pivot and is also provided with a locking finger which is adapted to have locking engagement with the ring holder as the latter 70 is turned laterally about the guiding projection. The guiding projection is shown at 11 and it is herein illustrated as being formed by cutting and bending up a portion of the rail plate adjacent the edge thereof 75 although such guiding projection might be situated at a distance from said edge without departing from the invention. In the preferred embodiment of my invention the end of the material which forms this guiding projection is bent over to form the lip 12 which lies substantially parallel to the rail plate. The opening in the ring holder adapted to receive the guiding projection is herein shown at 13 and is in the form of a 80 notch formed in the edge of the ring holder, but this opening would, of course, have a position corresponding to that of the guiding projection.

The locking member is preferably situated on the opposite side of the rail plate from that of the guiding projection, and it is herein illustrated as in the form of a locking finger 14 which extends parallel to the rail plate and beneath which the ring holder 95 may pass and which is provided with a locking projection or point 15 that is adapted to engage an aperture or indentation 16 formed in the ring holder. This locking member may conveniently be made by slitting the 100 ring rail and bending the slit portion up to the proper shape. The ring holder is provided with an opening or notch 17 which is situated so that when the ring holder is applied to the rail plate the locking member 105 14 will pass through the notch so as to be

situated above said ring holder. In applying the ring holder to the rail plate the guiding projection 11 is slipped into the notch or opening 13 and the ring holder is then positioned so that the notch 17 therein will be located in alignment with the locking member 14 and said ring holder is dropped onto the rail plate, thus permitting the locking member to pass through the notch or opening 17, as shown in dotted lines Fig. 1. The ring holder is then swung laterally about the guiding projection 11 as a center during which movement the portion 18 of the ring holder adjacent the notch 7 passes under the locking member 14 and when the shoulder or edge 19 of the notch 17 brings up against the vertical portion 20 of the locking member, the ring holder will be properly positioned concentric with the rail plate. The locking member may be so constructed that the frictional engagement between it and the upper surface of the ring holder will hold the latter in its adjusted position, but I prefer to make the locking member with the locking point 15 as above described which snaps into the indentation 16 and thus more securely holds the ring holder in position. The ring holder can be readily detached by swinging it laterally about the guiding projection as a center into the dotted line position Fig. 1 and then moving it vertically away from the rail plate to carry the ring holder above the locking member 14. 23 indicates a traveler clearer.

35 While I have illustrated herein the preferred embodiment of my invention I do not wish to be limited to the constructional details shown.

Having fully described my invention,

what I claim as new and desire to secure by Letters Patent is:—

1. In a spinning ring, the combination with a rail plate having a guiding projection and a resiliently sustained locking member which extends parallel to the upper face 45 of the rail plate, of a ring holder having an opening to receive the guiding projection and adapted to turn laterally about said guiding projection as a center and having another opening to receive the locking member whereby when the ring holder is turned laterally about the guiding projection a portion of the ring holder will pass beneath the resiliently-sustained locking member and be frictionally engaged thereby.

2. In a spinning ring, the combination with a rail plate having a guiding projection and a locking member which extends parallel thereto, of a ring holder having an opening to receive the guiding projection and adapted to turn laterally about said guiding projection as a center and having another opening to receive the locking member whereby when the ring holder is turned laterally about the guiding projection a portion of the ring holder will pass beneath the locking member, said locking member having a locking lip adapted to enter a recess in the ring holder when the latter is properly positioned.

In testimony whereof, I have signed my name to this specification, in the presence of two subscribing witnesses.

GEORGE L. PIERCE.
